UNITED STATES PATENT OFFICE.

ALBERT J. MEIER, OF GLENDALE, MISSOURI.

BAG-HOUSE.

1,030,477.

Specification of Letters Patent. Patented June 25, 1912.

Application filed May 19, 1911. Serial No. 628,341.

To all whom it may concern:

Be it known that I, ALBERT J. MEIER, a citizen of the United States, and residing at Glendale, in the county of St. Louis and State of Missouri, have invented certain new and useful Improvements in Bag-Houses, of which the following is a specification.

This invention relates to bag-houses used in metallurgical practice for saving the fume and dust by filtration of the fume through bags of cloth.

A bag-house as used in metallurgical practice is a building or structure divided off by a horizontal partition into a bag chamber and a fume inlet and deposit chamber or cellar. The partition is formed with a number of holes provided with thimbles. The bags are tubes of cotton or woolen cloth about 18 inches in diameter and from 20 to 30 feet long. These bags are closed at one end and suspended by their closed ends in the bag chamber and with their open ends over the holes and tied to the thimbles in the partition. The gas or fume is conducted into the inlet chamber and is drawn through the bags by means of an exhaust fan connected to the bag chamber. By passing the fume through the bags, the fume and dust will be deposited on the interior walls thereof and is periodically removed by shaking the bags, the dust dropping into the deposit chamber or cellar where it is ignited and sintered together so that it can be smelted. While the bags are shaken the damper between the inlet pipe or flue and the deposit chamber must be closed in order that the pressure on the interior and exterior of the bags will be equalized.

Heretofore the operation of shaking the bags has been entirely manual. The damper was closed and an operator was then required to enter the bag chamber and shake the bags. Since the operator is subjected to the poisonous gases in the bag chamber, especially where a lead fume is treated, the operation is not only disagreeable but dangerous as well. On the other hand the manual operation is exceedingly slow and tedious and therefore is done at comparatively long intervals, so that the efficiency of the apparatus is very much reduced on account of the clogging taking place between successive shaking operations.

One of the objects of this invention there-

fore is to construct a bag-house, and provide operating means for shaking the bags which will not require the operator to enter the bag chamber, and to construct the operating means so that the bags will be shaken intermittently and at comparatively short intervals.

Another object is to combine with bag shaking means, mechanism for closing the damper between the inlet chamber and the flue while the bags are being shaken.

Another object is to construct the bag shaking means so that it will operate to shake the bags in sections, and to provide means constructed to cut off the fume supply from the section which is to be shaken, leaving the fume turned on to the other sections.

Another object is to provide a novel supporting means for the bags to permit easy shaking operation thereof and to permit a row of bags to be shaken as a unit.

Further objects will appear from the detail description taken in connection with the accompanying drawings in which:

Figure 1 is a plan view partly in section of a bag-house and showing one embodiment of this invention, and Fig. 2 is a section on the line 2-2 Fig. 1.

Only so much of a bag-house is shown as to illustrate and permit explanation of this invention, since bag-houses are well known to those skilled in the art.

Referring to the accompanying drawings, 10 designates one of the walls of the structure forming the bag-house, and 11 the partition or plate separating the bag chamber A from the inlet chambers or cellars. The space below the partition is divided by 15 walls 12, 13, 14, etc., into a number of cellars B, C, D, E, etc. A gas main or fume flue G runs along the ends of the cellars and opens therein by means of damper controlled ports or passages, b being 20 the port or passage connecting the cellar B with the flue, but it will be understood that each cellar has its separate damper controlled passage or port connecting it with the flue.

The partition plate has formed therein rows of holes 15 provided with thimbles 16. The bags 17 are suspended from bars 18, the upper ends of these bags being closed and connected to the bars by means of eyes 19, 25 and the lower open ends of the bags extending over the holes 15 and being tied to the

thimbles 16. The bags are suspended in rows, each row being supported by a bar 18, and these bars being supported by means of springs 20 from beams 21, there being 5 preferably a spring opposite each suspension point of a bag.

The bars 18 are provided at one of their ends with rolls 22 adapted to be engaged by shaking cams 23 on an operating shaft 24. 10 This shaft extends across the building and is driven at a slow speed and in a clockwise direction from a suitable motor 25 through a countershaft 26, a worm and wheel 27, and a second countershaft 28. A rod 18^a guides 15 the bars 18.

Three rows of bags open from a single cellar and form a section, and the bags of a section are simultaneously operated by means of the cams 23. As the shaft 24 rotates, the cams 23 will engage the rolls 22 and move the bars 18 lengthwise or laterally in the direction of their length against the tension of the springs 20 supporting them. 20 After these cams pass the rolls, the bars will 25 be released and will be returned with the bags thereon to original position. This releasing movement will cause the bars 18 supporting the bags to be shaken laterally so as to shake the deposited matter into the 30 cellars. The cams for the bars of a section are mounted on the shaft 24 in the same angular relation so that the bars will be operated simultaneously to shake the bags of a section simultaneously. The sets of 35 cams for operating the bags of the different sections are however displaced angularly so that the bag sections will be shaken successively. Thus the sections will be shaken successively in the order B, C, D, E, etc.

40 While the bags of a section are being shaken, the damper for that section must be closed in order to cut off the fume from the cellar of that section. Means are therefore provided for automatically closing the 45 damper of the section which is to be shaken. Each bag section is provided with a support 29 for a lever, one arm 30 of which is arranged to be engaged by a damper cam 31 on the shaft 24, the other arm 30^a being 50 connected with an endless cable 32 passing over suitable pulleys and also connected with the sliding rod 33 of a damper 34 controlling port or passage b. This damper is normally maintained in open position by 55 means of a weight 35. It will be understood of course that a damper is provided for each passage of a bag section, and that each section is similarly controlled. As the shaft 24 revolves, and while the cams 23 move the 60 rods 18 of a bag section to the left, the cam 31 for that section will move the lever and close the damper for that section, so that the damper will be closed when the rods 18 are released to shake the bags. The 65 damper cams 31 of the different sections

are angularly displaced on the shaft 24 so that the dampers for the different sections will be closed successively and in the same order as the bags are shaken by the shaking cams 23. After the bags have been shaken 70 the damper lever will be released by the damper cam and the weight 35 will return the damper to open position. It will therefore be seen that mechanical operating means are provided for shaking the bags, 75 and these bags are shaken in sections and the sections are shaken successively and in rotation, i. e., after the last bag section has been shaken the first section will be shaken next. While each section is shaken, the 80 damper for that section is automatically closed and thereafter automatically opened after the bags have been shaken. The principal shaking movement is a lateral one, although the movement is a compound lateral 85 and vertical movement, this compound movement being permitted by the method of suspending the bags by means of springs. After the bags are released by the bag shaking cams, the suspended construction permits a free vibratory movement of the rod supports, and this results in a thorough agitation of the bags and in the deposit being thoroughly shaken down into the 90 cellars. The construction results in a simple 95 mechanism which can be extended to operate any number of sections by merely lengthening the operating shaft 24 and adding parts connected thereto and operated therefrom.

100 By means of this construction the bags can be shaken automatically so that it is unnecessary for the operator to enter the bag chamber or the building, whereby he will not be subjected to the poisonous gases. This also results in efficiency of filtering, 105 since the bags are shaken at comparatively short intervals so that the bags will always be clean. Each section is shut down for only a very small part of the time so that the interruption to filtering will be slight.

110 It is obvious that various changes may be made in the details of construction without departing from this invention, and it is therefore to be understood that this invention is not to be limited to the specific construction shown and described.

Having thus described the invention what is claimed is:

1. In an apparatus of the class described, 115 a structure having a bag chamber and a plurality of cellars below said bag chamber and separated one from the other by transverse partitions, a plurality of bags suspended in rows in said bag chamber and opening from said cellars, one section from each cellar, dampers for said cellars, and interconnected means for closing said dampers in succession and for shaking the bag sections connected to the cellars which the 120 125 130

dampers control in the same order as said dampers are operated.

2. In an apparatus of the class described, a structure having a perforated horizontal partition therein to form a bag chamber, a plurality of transverse partitions dividing the space below said perforated partition into a plurality of cellars, a plurality of bags suspended in rows in said bag chamber and opening from said cellar, a main flue connected to said cellars, dampers between said flue and cellars, and interconnected means for closing said dampers in succession and for shaking the bag sections connected to the cellars which the dampers control in the same order as said dampers are operated.

3. In an apparatus of the class described, a structure having a bag chamber and a plurality of cellars below said bag chambers and separated one from the other by transverse partitions, a plurality of bars movably supported in said bag chamber, a row of bags suspended from each bar and opening from one of said cellars, a plurality of rows of bags opening from each cellar and forming a bag section, and interconnected means for closing said dampers in succession and for shaking the bag sections connected to the cellars which the dampers control in the same order as said dampers are operated.

4. In an apparatus of the class described, the combination of a support, a row of bags suspended therefrom, and means for imparting a movement to said support and the bags thereon in a direction along the row to shake the bags.

5. In an apparatus of the class described, the combination of a movably supported bar, a row of bags suspended therefrom, and means for moving said bar in the direction of its length to shake the bags thereon.

In an apparatus of the class described, the combination of a support, a bag, and a suspending spring connected at its upper end to the support and at its lower end to the bag and constructed to suspend the bag for free lateral and vertical movements.

50 7. In an apparatus of the class described, the combination of a support, a bar, a plurality of bags suspended from said bar,

springs for suspending said bar connected at their upper ends to said support and at their lower ends to said bar, and operating means for moving said bar to shake the bags thereon.

8. In an apparatus of the class described, the combination of a bar, a plurality of bags suspended therefrom, means for loosely suspending the bar, and operating means for moving said bar lengthwise to shake the bags thereon.

9. In an apparatus of the class described, the combination of a lengthwise movable bar, a plurality of bags suspended therefrom, and a cam adapted to move the bar lengthwise and release the same to shake the bags thereon.

10. In an apparatus of the class described, the combination of a bar, a plurality of bags suspended therefrom, springs for suspending said bar, and a cam adapted to engage the end of the bar and release the same to shake the bags thereon.

11. In an apparatus of the class described, the combination of a bar, a row of bags suspended from said bar, and means for loosely suspending said bar at the points of connection of the bags thereto.

12. In an apparatus of the class described, the combination of a plurality of suspended bars, bags supported therefrom, a drive shaft extending across said bars, and independent connections between said bars and shaft constructed to permit said shaft to move said bars endwise.

13. In an apparatus of the class described, a structure having a bag chamber and a plurality of cellars below said bag chamber, bags supported in said bag chamber and opening from said cellars, dampers for said cellars, a drive shaft extending across said structure, independent connections from said shaft constructed to shake said bags in sections, and independent connections from said shaft to said dampers adapted to close them individually.

In testimony whereof I affix my signature in presence of two witnesses.

ALBERT J. MEIER.
